UNITED STATES PATENT OFFICE.

GEORGE P. FENNER, OF NEW LONDON, CONNECTICUT.

AIR-CUSHIONING DEVICE FOR PRINTING-PRESSES.

SPECIFICATION forming part of Letters Patent No. 272,673, dated February 20, 1883.

Application filed August 19, 1882. (No model.)

To all whom it may concern:

Be it known that I, GEORGE P. FENNER, a citizen of the United States, residing at New London, in the county of New London and State of Connecticut, have invented new and useful Improvements in Air-Cushioning Devices for Printing-Presses, of which the following is a specification.

This invention relates to an improvement in that class of printing-presses in which the momentum of the bed is checked by air-cushions, the peculiar devices which form the subject-matter of my invention being pointed out in the following specification.

15 In the accompanying drawings, Figure 1 represents a sectional side view. Fig. 2 is an end view.

Similar letters indicate corresponding parts.

In the drawings, the letter A designates the frame, on which are formed the guideways for the bed B. On the under side of this bed is firmly secured a yoke, C, which forms the support for a rod, D. This rod is stationary, and on it, near its ends, are secured the pistons E 25 E, which fit the air-cylinders F F. These cylinders are firmly secured to the frame A. They are open at their inner ends and closed at their outer ends, and as the bed reciprocates the pistons E E enter the cylinders F F, and 30 as the air in these cylinders is compressed air-cushions are formed for the purpose of checking the momentum of the bed. In printing-presses of this class it happens frequently that pieces of paper or other obstructions get caught

35 between one of the pistons E and its cylinder F, thereby interfering with the operation of the machine. This difficulty I have overcome by means of a shield, G, which is fastened to or held in a manner to protect the inner ends 40 of the cylinders F F, and extends through the yoke C, said yoke being made open, as shown in Fig. 2, so as to afford room for the passage of the shield. This shield, which is semi-cylindrical, covers the pistons E E, and it effect- 45 ually prevents pieces of paper, dust, or other obstructions from catching between the pistons and their cylinders. The shield G may, however, be made in two sections, each sec- 50 tion being fastened at its outer end to or over one of the air-cylinders and at its inner end to

the yoke, and in this case it is not requisite that the yoke shall be open.

The air-cushions, formed by the cylinders F F and pistons E E, are of great value when the printing-machine is driven by power; but in many cases it is desirable to move the machine by hand, and in these cases the operation of moving the machine is materially facilitated if the action of the air-cushions is interrupted for the time being. This object I have accomplished by the following means: Beneath the bed, or in any other convenient position, is situated a faucet, H, the plug of which connects by a lever, I, with a rod, J. From the shell of the faucet extend two pipes, K K, to the outer ends of the cylinders F F. By moving the plug of the faucet into the proper position the inner ends of the pipes K K are brought in communication with the open atmosphere, and the action of the air-cushions is interrupted, because if one of the pistons E enters its cylinder the air contained in this cylinder is free to escape and no air-cushion is formed. This object may also be attained by providing the inner end of each of the pipes K K with a separate stop-cock, both such stop-cocks being operated by means of one and the same lever or equivalent device.

The position of the plug of the faucet H can be controlled by the rod J, which is guided in the frame A and pivoted to the lower end of a lever, L, (best seen in Fig. 2,) and which carries the belt-shipper M, said rod J being arranged to move horizontally across the frame of the machine, and connected with the plug of the faucet by a vertically-arranged link, I, so that when said rod is moved so as to throw the belt on the loose pulley the plug of the faucet is turned, through the medium of the link I, so as to open the communication between the inner end of the pipes K K and the open atmosphere, and the printing-machine can be easily set in motion by hand; but if the rod J is moved so as to throw the belt upon the fast pulley the communication between the inner ends of the two pipes and the open atmosphere is closed, and the action of the air-cushion is restored.

What I claim as new, and desire to secure by Letters Patent, is—

1. The combination, in a printing-press, of a supporting frame-work, a reciprocating bed thereon, a yoke secured to the under side of the bed, the pistons carried by the yoke, the cylinders stationary on the frame-work, and a shield arranged longitudinally under the reciprocating bed and between the arms of the yoke attached thereto, the ends of the shield extending respectively over the open ends of the cylinders, substantially as and for the purpose described.

2. The combination, in a printing-press, of the supporting frame-work, the reciprocating bed thereon, the pistons carried by and moving with the bed, the open cylinders stationary on the frame-work, the pipes connected

with the closed ends of the cylinders, the faucet or plug connected with and common to the pipes of both cylinders, the horizontally-movable transverse slide-rod connected with the faucet or plug, the belt-shipper carried by said rod, and a lever for shifting the latter horizontally to shift the belt and cause the vertical link to actuate the faucet or plug, substantially as described.

25

In testimony whereof I have hereunto set my hand and seal in the presence of two subscribing witnesses.

GEO. P. FENNER. [L. S.]

W. HAUFF,
